(57) **CLAIM**

The ornamental design for a bracelet, substantially as shown in the attached drawings.

DESCRIPTION

FIG. 1 is a top perspective view of a bracelet;

FIG. 2 is a bottom perspective view thereof;

FIG. 3 is a top view thereof;

FIG. 4 is a bottom view thereof;

FIG. 5 is a front view thereof;

FIG. 6 is a back view thereof;

FIG. 7 is a right side view thereof;

FIG. 8 is a left side view of the bracelet design;

FIG. 9 is a perspective view of the bracelet design shown in a double-wrapped configuration on the wrist of a person; and,

FIG. 10 is a perspective view of the bracelet design in a double-wrapped configuration.

The break line in FIGS. 1-8 omit portions of the bracelet for ease of illustration. FIGS. 9 and 10 show the length of the bracelet as claimed. The broken lines showing a wrist and hand in FIG. 9 are for environmental purpose and for no part of the claimed design. The broken lines showing lettering on the tab portion of the bracelet in FIGS. 1, 3, 9, and 10 illustrate portions of the bracelet that form no part of the claimed design.

1 Claim, 4 Drawing Sheets
